ELECTRICAL MUSICAL INSTRUMENT

John M. Hanert, Park Ridge, Ill., assignor to
 Hammond Instrument Company, Chicago, Ill.,
 a corporation of Delaware

Application December 23, 1944, Serial No. 569,567

25 Claims. (Cl. 84—1.01)

1

My invention relates generally to electrical musical instruments and more particularly to an improved instrument which is voice controlled and thus may be "played" by anyone capable of carrying a tune by singing, humming or whistling.

In many musical presentations the music could be greatly improved if there were provided some means for accompanying the singer without requiring the presence of a trained musician for the playing of the musical instrument. Furthermore, many people who enjoy music are deprived of the pleasure of producing instrumental music because of their inability or disinclination to pursue the long period of education and practice usually required to enable them to become proficient.

It is therefore the fundamental object of my invention to provide an improved musical instrument in which the operation of the instrument is controlled mainly by the pitch and loudness of the voice of the performer, in which various manually operable amplitude controls are provided, in which the music produced may be in any desired pitch range irrespective of the pitch of the voice used to control the instrument, and in which octave coupler effects may be obtained.

A further object is to provide an electrical musical instrument in which the pitch and loudness of the tones produced are controlled respectively by the pitch and loudness of voice or other sound made by the performer, but in which the pitch of the output tone is always exactly of a frequency of a note of the tempered musical scale even though the controlling voice or sound is slightly off pitch.

A further object of the invention is to provide the output of the generating system of a musical instrument with a plurality of rectifying means to change the effective tone quality, such rectifying means having a common manual control to render them effective or ineffective.

A further object is to provide an electrical musical instrument responsive to the pitch of an input wave, which is capable of producing pleasing musical tones of corresponding pitch or of octavely related pitches, and of selected tone quality.

Other objects will appear from the following description, reference being had to the accompanying drawings in which:

Figs. 1, 1a and 1b together constitute a schematic wiring diagram of the instrument; and

Figs. 2, 3 and 4 illustrate the forms of the signal waves appearing in various circuits of the instrument.

As shown in Fig. 1 the input to an amplifier 10 may be supplied by a microphone 12, which

may be of the usual type, but is preferably a throat microphone, or may be supplied from a special crystal microphone 14, depending upon the position of a single pole double throw switch

5 16. The crystal microphone 14 is preferably mounted in a case 18 having a rubber tube 20 connected thereto, the rubber tube 20 being connected to a glass or similar tube 22 adapted to be inserted in the oral cavity of the performer. The 10 other end of the tube 22 is closed by a suitable flexible diaphragm 24 by which saliva is excluded from the tube 22, while permitting free transmission of sound from the oral cavity to the microphone 14.

15 The amplifier 10 is preferably of the type in which due to the provision of one or more filtering meshes, lower frequencies are amplified to a considerably greater extent than higher frequencies, as indicated by the frequency response curve

20 13, for convenience shown directly on the block representing the amplifier 10. By virtue of this response characteristic of the amplifier, the fundamentals of musical tones picked up by the microphone will be amplified to a greater extent

25 than the harmonics. In most musical tone qualities the fundamental is of substantial amplitude so that even if a particular quality of tone picked up by the microphone has a second or higher harmonic of greater amplitude than the fundamental, the fundamental will nevertheless be of greater amplitude in the output of the amplifier by virtue of the progressively lesser amplification of the higher frequencies.

The output of the amplifier 10 is transmitted through a coupling capacitor C26 to a conductor

35 28, the latter having a plurality of decoupling resistors R30 respectively connecting the conductor 28 to the control grids 32 of pentodes 34. There are preferably 18 pentodes 34, with their associated circuits, employed in the instrument,

40 of which a representative group of four are illustrated in Fig. 1. Connected to the grid 32 of each of these pentodes is a parallel resonant mesh comprising an inductance L35 and a capacitor C36, these meshes being tuned to resonate at the

45 semitone intervals in the usual vocal range from the pitch A2 at 220 C. P. S. to the pitch D4 having a frequency of 587.3 C. P. S. The cathodes 40 of the pentodes 34 are connected to a common conductor 42 which is connected to ground

50 through a common self-bias resistor R44 bypassed by a capacitor C45. The resistor R44 is of relatively high value such that the voltage drop across it, due to the flow of plate current through any one of the pentodes 34, will bias the other pentodes beyond cutoff for signals of but

2

slightly lesser amplitude than that which is impressed upon the grid of the conducting pentode. The suppressor grids 46 of the pentodes 32 are likewise connected to the conductor 42 while the screen grids 48 thereof are connected to a suitable source of constant potential indicated as +30 v. The plate 50 of each of the pentodes 34 is supplied with plate current from a suitable source, indicated as a terminal +30 v., through a load resistor R52 which has a capacitor C54 connected in parallel therewith.

A pentode 56 has its cathode 58 and suppressor grid 60 connected to the +30 v. terminal of a suitable power supply while its control grid 62 is connected directly to the plate 50 of the pentode 34. The screen grids 64 of all of the pentodes 56 are connected by a common conductor 66 and a voltage dropping resistor R68 to a terminal +250 v. of the power supply. The anodes 70 of the pentodes 56 are connected to suitable source of operating potential, such as a terminal +250 v. of the power supply, through the windings of relays 72 respectively.

From the foregoing it will be apparent that when an audible signal such as produced by singing, humming or whistling of the performer is supplied to one of the microphones, predominantly the fundamental frequency of such signal will be transmitted through and amplified by the amplifier 10 and impressed across the various resonant meshes L35—C36. That particular one of these resonant meshes which is tuned to a frequency nearest that of the fundamental of the controlling audible signal will cause a higher amplitude signal to be impressed upon its associated grid 32 than is impressed upon the remaining grids 32, and thus its associated pentode 34 will be rendered conductive. Upon the flow of plate current through such pentode the voltage drop across the common self-bias resistor R44 will cause the potential on the cathodes 40 of the remaining pentodes to swing materially in a positive direction, so that such remaining tubes will be effectively "locked out" and frequencies corresponding to those of the tuned meshes associated with them would have to be of greater amplitude in order to take away the control from the first pentode. When one of the pentodes 34 is rendered conducting, the flow of plate current, due to the drop across resistor R52 causes the potential of the grid 62 to drop with resultant pronounced reduction in plate current and deenergization of its associated relay 72.

The pentode 34, associated with the mesh L35, C36 of the highest resonant frequency, operates in the same manner as the other pentodes but does not have a pentode 56 or relay 72 coupled to its output. The reason for this will appear more clearly hereinafter but in general is based upon the fact that the instrument is normally tuned to generate a musical tone corresponding to the highest frequency mesh and it is therefore unnecessary to provide any tuning control for the musical instrument when the audio input frequency corresponds to this highest frequency.

From the foregoing it will appear that all of the relays 72 will normally be energized and only one relay, in the channel corresponding to the highest amplitude-frequency in the output of amplifier 10, will be deenergized. Thus, if the input signal consists of a pitch glissando tone, the relays 72 corresponding to the pitch range of the tone will be operated sequentially, one at a time. Each relay 72 is provided with a switch

74 which is normally open, i. e. when the relay 72 is closed. The switches 74 when energized connect the junctions between a series of tuning capacitors C76 (Fig. 1a) with a grounded conductor 78. The capacitors C76 constitute part of the tuning circuit of a master oscillator comprising a pentode 78, the output of which is supplied to a rectifying triode 80. The input circuit of the pentode 78 includes not only the series of capacitors C76 but the parallel connected inductance L82 forming the primary winding of a tuning coil L84, the secondary winding L86 of which is connected between ground and the cathode 88 of the pentode 78.

A tap on the inductance L82 is connected to a vibrato apparatus 90 which may be of the construction disclosed in my prior Patent No. 2,301,871, this vibrato apparatus preferably having a control 91 by which it may be turned off or on.

The pentode 78 has its output coupled to the input of the triode 80 which operates in a manner to provide a rectified output signal in the form of a relatively sharp pulse wave. The output of triode 80 is coupled to the input circuits of a pair of intercoupled triodes 94 and 95 which are supplied with suitable circuit elements so that each of these tubes is responsive only to alternate pulses and these tubes thus constitute a pulse or frequency divider stage. This dividing function of the triodes 94, 95 is more fully disclosed in my copending application, Serial No. 519,838, filed January 27, 1944, and since abandoned.

An output signal of one-half the frequency of the oscillator 78 is supplied to the second divider stage through a coupling condenser C96 connected between the plate of triode 95 and the grid of triode 98, the latter constituting a

means for rectifying and sharpening the wave front of the pulse appearing in the output of triode 95. This pulse is impressed upon the grids of intercoupled triodes 99 and 100, which together with the triode 98 constitute the second frequency divider stage. The third, fourth and fifth frequency divider stages are similar to the first and second stages and are therefore illustrated as blocks 103, 104 and 105 respectively. Thus the first divider stage is capable of producing a signal frequency one-half that of the oscillator 78 and the second, third, fourth and fifth divider stages produce signals which are respectively $\frac{1}{4}$, $\frac{1}{8}$, $\frac{1}{16}$ and $\frac{1}{32}$ of the frequency of the oscillator 78.

The output signal from the pulse sharpening triode 80 is derived from the junction of voltage divider resistances R106 and R107 which together constitute the plate load for triode 80. A blocking capacitor C108 connects the junction of resistors R106 and R107 with the conductor 110. A line resistor R112 is connected between the conductor 110 and ground. In a similar way the output of the first frequency divider stage is impressed upon a conductor 114, that of the second divider stage upon a conductor 115, and that of the third, fourth and fifth divider stages impressed upon conductors 116, 117 and 118 respectively.

The conductors 110 and 114 are respectively connected to the plates 120 of a twin diode rectifier tube 122, the cathodes 124 of this tube being connected to ground through a conductor 125, resistor R126, and resistor R128, the latter having a by-pass capacitor C130 connected in parallel therewith. The resistor R128 with its

by-pass capacitor C130 provides self-bias for the triodes 80, 94, 95, 98, 99 and 100 and the corresponding triodes in the remaining frequency dividing and rectifying stages.

In a similar manner the signal conductors 115 and 116 are connected to the plates of a twin diode rectifier tube 130, while the signal conductors 117 and 118 are connected to the plates of a twin diode rectifier 132. The cathodes of the rectifier tubes 130 and 132 are likewise connected to the conductor 125. A switch 134 (Fig. 1a) is arranged to connect the conductor 125 to ground and, when the switch is in the full line position shown, the three twin diodes 120, 130 and 132 are rendered effective to rectify the output signals of the pulse sharpening triode 80 and the several divider stages by cutting off the positive peak portions of the signal wave outputs of these stages. When the switch 134 is moved to its dotted line position, the cathodes of the twin diodes attain substantially the relatively high positive potential of the cathodes of the triodes 94 and 95, 98, 99 and 100, etc. so that transmission of the output signals from the various stages is not affected by the twin diodes. Since the effective power of the output signals is substantially doubled when the switch 134 is moved to its dotted line position, this switch is arranged to connect an attenuating resistance R138 in the output circuit, this resistance operating to compensate for the increase in the output of the oscillator and divider stages.

The output signals derived from the various divider stages are of the wave shape illustrated in Fig. 2. This generally rectangular wave shape represents a musical tone signal having an undesirably strong fundamental and also an undesirably long harmonic series. To obtain more artistic tones, the rectangular wave shape shown in Fig. 2 is modified to that shown in Fig. 3 by means of resistance capacitor meshes which are associated with the output circuits of each of the frequency divider stages. Each of these output circuits comprises a current limiting capacitor C137 which is effective to reduce the undesirable intensity of the fundamental component, and a capacitor C139 which is effective to attenuate the undesirable high harmonics of the tone whose wave shape is shown in Fig. 2. A resistor RX1 is connected in parallel with capacitor C139 and a line resistor RX2 is connected between ground and each of the signal lines, such as line 115. Capacitors C137 and C139 cause the signal wave to be changed to the modified symmetrical wave shape shown in Fig. 3. This wave shape corresponds closely to those of the tones produced by the woodwind family of musical instruments comprising very predominantly the odd harmonic series and is further of a wave shape suitable for the input to the rectifying twin diodes 120, 130 and 132.

Each of these diodes is effective to attenuate the positive peak portion of the wave, thereby destroying the symmetry of the resulting wave shape, whenever the switch 134 is connected in its full line position. The attenuation of the positive peaks of the wave shown in Fig. 3 results in a wave form representing a new harmonic series, the wave shape being shown in Fig. 4. This wave shape is characteristic of an entirely different tonal family containing all of the harmonics, and is of the string family of orchestral tones.

By movement of the switch 134 to its dotted line position, the signal applied to the output of

the instrument may be of the character of Fig. 3, whereas when the switch is moved to its full line position the signal supplied to the output will be of the character represented by the wave of Fig. 4. Thus by the operation of a single switch the tone quality of the output signals of all of the frequency divider stages may be radically altered to obtain novel and interesting musical effects.

Conductors 110 and 114 to 118 inclusive are adapted to be coupled to the input of a pre-amplifier triode 140 by selective operation of stop tablets 142 in the well known manner as disclosed, for example, in my prior Patent No. 2,357,191 dated August 29, 1944. The output of the preamplifier 140 is suitably modified by one or more of a plurality of tone control filtering networks 141 by opening one or more of a plurality of switches 143, and impressed upon the primary winding of a transformer T144. The secondary winding of transformer T144 has a center tap 146, the potential of which is adapted to be controlled by a volume control device 148, the normal voltage of this center tap being controlled by adjustment of an adjustable resistor R150.

The terminals of the secondary winding of the transformer T144 are connected to the control grids 148 and 149 of volume and tone envelope controlling pentodes 150 and 151 respectively. It will be understood that the biasing potential on the grids 148 and 149 is determined by the potential at the center tap 146. In addition to being controllable by the volume control device 148 and the normal adjustable volume control R150, there are provided other means for determining this potential which will be described hereinafter. For the present it will be noted that the push-pull output of the control tubes 150 and 151 is supplied to a push-pull power amplifier 152 and that the latter energizes a speaker 154.

In using the instrument it is desirable that the intensity of sound output, in addition to being controllable by the volume control device 148 shall be automatically controlled by the intensity of the sound input, i. e. the loudness of the voice, humming, or whistling, and this latter result is automatically accomplished as will now be described. A conductor 160 is connected to the output terminal of the amplifier 10 and supplies an input signal to a triode 162 through a blocking condenser C164. The triode 162 is self-biased and is coupled with a full wave rectifier tube 164 by means of a coupling transformer T166. Since the anodes 168 of the rectifier tube 164 are respectively connected to the terminals of the secondary winding of the transformer T166 and the cathode 169 thereof is connected to the grounded center tap of this secondary winding through a rectifier load resistor R170 and filter capacitor C172, the D. C. potential on the cathode will be substantially proportional to the amplitude of the output signal of the amplifier 10. The cathode 169 is normally connected by a conductor 174 and a switch 176 to the center tap 146 of the coupling transformer T144. The potential on the center tap 146 determines the grid bias and hence the degree of amplification obtained through the pentodes 150 and 151. Thus when the switch 176 is in its full line position the degree of amplification obtained by the control pentodes 150 and 151 will depend upon the amplitude of the output signal from the amplifier 10.

It is desirable to cut off the control pentodes 150 and 151 when no signal is being supplied

to the input of the amplifier 10, but at the same time, it is essential that these control pentodes commence to transmit a signal shortly after the output of the amplifier 10 exceeds a predetermined low threshold value such as represented, for example, by the output of the amplifier when the player is not singing, whistling or humming into one of the microphones, in which case the output of the amplifier would be merely noise and not significant. This is accomplished by means of a triode 180, the control grid 182 of which is connected to the conductor 160 through a capacitor C184. The control grid 182 has its biasing potential determined by an adjustable voltage divider resistor R186, a sliding contact of which is connected to the grid 182 through a grid resistor R183, and the terminals of which are respectively connected to ground and a suitable source of negative biasing potential indicated as -25 v. By properly adjusting the position of the slider on the adjustable voltage divider R186 the bias on the triode 180 may be made sufficient to maintain the triode cut off until the amplitude of the signal output of the amplifier 10 exceeds the noise threshold to a significant extent. This will occur whenever the player whistles, hums or sings into one of the microphones. When the output signal of the amplifier 10 exceeds the bias potential on the triode 180, the latter will conduct the signal. The winding of a relay 190 forms the plate load impedance for the triode 180, being connected between the plate and a suitable source of plate potential indicated as +B. A condenser C192 is connected in parallel with the winding of relay 190, this condenser being of small value so as to smooth out fluctuations in the plate current flow resultant from the fact that an audio frequency current is impressed upon the grid 182. The relay, upon energization, is adapted to open a normally closed switch 194 and thus break the circuit between conductors 195 and 196. Energization of the relay also results in closure of a switch 198 which connects a conductor 200 to ground. It will be noted that conductor 195 is connected to a terminal 202 (Fig. 1b) which is normally at a suitable operating potential for the screen grids 204 of the control pentodes 150 and 151, this potential being determined by a suitable voltage divider comprising resistors R206 and R207 connected between a terminal of the power supply indicated as +300 v. and ground. A normally operable switch 208 is adapted to connect the junction 202 with the screen grids, the switch 208 being closed when it is desired to produce a steady organlike sustained tone envelope and open when it is desired to produce a piano or banjo-like percussive tone envelope.

It will thus appear that the opening of the switch 194 by energization of the relay 190 has no effect upon the tone envelope when the switch 208 is closed, since the relay switch 194 and switch 208 are in parallel.

This percussion effect is produced by virtue of the fact that the normal screen potential at the junction 202 is impressed upon the screen grids 204 of the control pentodes 150, 151 through the conductors 195, 196 and switch 194, which circuit is interrupted whenever the relay 190 is energized to open switch 194. Whenever the switch 208 or relay switch 194 is opened, the potential on the screen grids 204 is sustained temporarily by a voltage storing capacitor C212 which is connected between the screen grids and a point of fixed potential, indicated as ground.

Since the control pentodes 150, 151 are of the remote cutoff type, the gradual reduction in screen potential due to the discharge of the capacitor C212 will cause a corresponding decrease in the gain of these tubes, and a musically desirable percussive tone envelope will result.

A single pole double throw switch 214 is mechanically connected to operate with the switch 176, both of these switches being either in the full line position shown in Fig. 1b, or in the dotted line position. When these switches are in the dotted line position, the tonal envelope produced is entirely independent of the performer's audible input to the amplifier 10, whereas when these switches are in the full line position, the envelopes of the tones produced by the instrument are related to the audible input to the amplifier 10 through the operation of the full wave rectifier tube 164.

When the switches 176 and 214 are in their dotted line positions the cathodes of the pentodes 150, 151 will be connected through conductor 215 to a junction 216 of a voltage divider network comprising resistors R218 and R219 connected between ground and a terminal of the power supply indicated as +300 v. Under these conditions the cathodes of pentodes 150, 151 are maintained at a potential of approximately +165 volts relative to ground, and the pentodes are fully cut off. Whenever the relay 190 is energized, as it is whenever a suitable audible signal is supplied to the amplifier 10, the relay switch 198 will be closed, connecting conductor 200 to ground. It will be noted (Fig. 1b) that the conductor 200 is connected to the junction point 216 through a resistor R222. The resistor R222 is thus effectively in parallel with the voltage divider resistor R219. The potential at the junction 216, and hence upon the cathode of pentodes 150, 151, is thereby reduced from a value of approximately +165 volts to a value of approximately +50 volts. This reduction of cathode potential is sufficient to render pentodes 150, 151 conducting. The extent of their conductivity is further controllable by means of the manually operated volume control device 148 which is effective to control the potential at a junction point 224. The potential at the junction 224 may be varied from ground to +50 volts in smoothly graded steps, depending upon the movement of the manual control of the volume control device 148. The junction point 224 is connected to the center tap 146 of the transformer T144 through a time constant mesh, comprising a resistor R226 and a capacitor C228. These latter circuit elements are effective to slow the rate at which the potential at the center tap 146 may change, and thus the change in gain of the remote cutoff pentodes 150, 151 is made smooth and gradual.

Opening a manually operated switch 230 renders effective a capacitor C232 which is then connected between the cathodes and center tap 146 of the pentodes 150, 151 whenever the switches 176 and 214 are in dotted line position. Thus, when the cathodes of the tubes 150, 151 suddenly change from +165 volts to +50 volts, due to connecting the conductor 200 to ground through the relay switch 198, the potential at the junction point 146 will change in a similar manner, thereby delaying the change in relative potentials of the grids and cathodes of the pentodes 150, 151. However, after the cathodes have attained the +50 volt potential, the potential at the center tap 146 will change to the potential at the junc-

tion point 224 at a slow rate, determined by the time constant of the combined condensers C228 and C232 with respect to the resistor R226. Thus a slow and smooth tonal attack is obtained. When the signal from the amplifier 10 disappears, deenergizing the relay 198 and opening its switch 198, the potential on the cathodes of the pentodes 150, 151 returns to +165 volts at a rate controlled by a relatively large capacitor C234 which is connected from the cathodes to ground.

When the switches 176 and 214 are in their full line positions the volume control device 143 is preferably not used and is left in the position of minimum volume. Under these conditions, the potential at the center tap 146 is determined by the potential of the cathode 169 of the full wave rectifier tube 184, which in turn is a function of the amplitude of the original signal supplied to the amplifier 10. A threshold control potentiometer 249 (Fig. 1b) is used to impart a threshold below which extraneous and undesired signals from the amplifier 10 are not effective to cause a signal to be heard from the speaker 154. The threshold potentiometer R249 thus serves a purpose similar to that of the potentiometer R186, since when the switches 176 and 214 are in the full line position, the latter potentiometer is not effective.

The resistor R178 (Fig. 1) will, in general, be of a low value by comparison with the resistor R226 (Fig. 1b) and therefore operation of the volume control device 143 will be ineffective under these conditions. A volume control R244 is provided for adjusting the overall gain of the amplifier.

From the foregoing it will appear that the instrument possesses a high degree of versatility as to volume, and as to the tone intensity envelopes which may be obtained by suitable operation of the various controls. For example:

1. When the switches 176 and 214 are in their full line positions and switch 208 is closed, the resulting tone intensity envelope will closely resemble that of the original signal supplied to the amplifier 10.

2. When the switches 176 and 214 are in their full line positions and the switch 208 is open, the initial attack and peak amplitude to which the signal rises will be controlled by the corresponding initial attack and the peak amplitude of the audible signal supplied to the amplifier 10, but the decay portions of the tonal envelope will be controlled by the manner in which the capacitor C212 discharges. Thus there will be produced a tone intensity envelope whose attack and decay are related to the attack and decay of the original signal supplied to the amplifier 10 but which is automatically made percussive in its overall effect.

3. When the switches 176 and 214 are in their dotted line positions with switch 230 closed and switch 208 closed, the resulting tonal envelope will be of a sustained organlike character having prompt attack and decay.

4. With the switches 176 and 214 in their dotted line positions, switch 230 open, and switch 208 closed, the tonal envelope will be of a sustained organlike character, but will be distinguished by slow and smooth attack similar to the attack of a bowed string instrument.

5. With the switches 176 and 214 in their dotted line positions and switches 208 and 230 open, the resulting tonal envelope will be of short duration, comprising a slow attack portion followed by a slow decay. The rate of attack and

decay will depend upon the values of the capacitors C212, C234 and C228.

In using the instrument the performer will sing, hum, whistle, or play on some musical instrument, a melody within the frequency range A2-220 C. P. S. and D4-587.3 C. P. S., which is a convenient frequency range for easy rendition of a tune. Depending upon which of the coupler stop tablets 142 is operated, the fundamental frequency of the output tone of the instrument may be in the range of from 1760 to 4698.63, 880 to 2349.32, 440 to 1174.66, 220 to 587.33, 110 to 293.66 or 55 to 146.83 C. P. S., or any desired combinations of these ranges which will correspond to the octave coupler effects obtained in organs. Thus the performer has at his command the ability to produce tones ranging from the lowest bass frequencies to the highest musical frequencies corresponding to the violin, flute and piccolo. Due to the fact that the frequency responsive control means for determining the pitch of the master oscillator responds in a manner to tune the master oscillator exactly to the pitches of the tempered musical scale, the performer may be considerably off key without changing the actual pitch of the tone produced. The only requirement upon the performer is that he shall hum, sing, whistle, or otherwise produce a musical tone, the pitch of which is closer to the desired note of the musical scale than to either of the adjacent semitones. This is a requirement which is easily met by most anyone capable of carrying a tune.

The tone produced may, as desired, contain a true pitch vibrato without any undesirable tremulant or unsteadiness.

The actual tone quality produced by the instrument may be selectively varied by opening one or more of the switches 143 and by operation of the tone family control switch 134. These controls will make it possible to vary the output tone over an extremely wide range of qualities including the orchestral flutes, woodwinds, reeds, strings, brasses, organ and percussion tones.

When using the instrument the performer will usually be in a position to hear the sound output of the speaker 154 and, since the tones produced will be at exactly the proper pitch, the performer will be able easily to detect the fact that he is not singing exactly on pitch by hearing beats between his voice tone and the tone of the speaker. The instrument may serve a very useful function in vocal instruction, since the student as well as the teacher may readily detect a failure to maintain proper pitch.

While I have shown and described a particular embodiment of the invention, it will be apparent to those skilled in the art that many modifications and variations thereof may be made without departing from the fundamental principles of the invention. I therefore desire by the following claims to include within the scope of my invention all such variations and modifications by which substantially the results of the invention may be obtained by the use of substantially the same or equivalent means.

I claim:

1. In an electrical musical instrument having an output system including amplifying and electroacoustic translating means, the combination of an electrical generator of musical frequencies, corresponding to the semitone intervals of the tempered musical scale, means for tuning the generator to various semitone intervals of the musical scale, a microphone, an amplifier for said

11

microphone, said amplifier having the characteristic of increasing gain for lower audio frequencies, a plurality of frequency responsive devices coupled to the output of said amplifier, said devices being responsive to frequencies corresponding respectively to the semitone frequencies to which said generator may be tuned, and means operated by said devices for changing the tuning of said generator to the musical semitone nearest in frequency to that of an input signal supplied to said microphone.

2. In an electrical musical instrument having an amplifier and electroacoustic translating means, the combination of an electric generator for electrically generating musical tone signals of the frequencies of the semitone intervals of the tempered musical scale, means coupling said generator to the amplifier, a plurality of devices for determining the pitch of the tone frequencies transmitted to said coupling means by said generator, means responsive to the frequency of an audible signal to cause the operation of one of said devices, and means controlled by the intensity of the audible signal to determine the amplitude of the tone frequencies transmitted to said coupling means by said generator.

3. In an electrical musical instrument having an amplifier and electroacoustic translating means, the combination of means coupled to the amplifier for electrically generating musical tone signals of the frequencies of the semitone intervals of the tempered musical scale, means responsive to the frequency of an audible signal to operate the generator tuning means to cause the latter to generate a frequency of a musical semitone closest to that of the controlling voice, and means responsive to the intensity of the audible signal to determine the amplitude of the tone signals transmitted from said generating means to the amplifier.

4. In an electrical musical instrument having an output system including an electroacoustic translating means and amplification means provided with a gain control, the combination of an electrical generator tunable to generate electrical signals corresponding to the semitones of the musical scale, means responsive to the pitch of a controlling voice to tune said generator to the semitone frequency most closely approaching that of the voice, and means responsive to the amplitude of the controlling voice for controlling the operation of the gain control means of the amplifier.

5. In an electrical musical instrument for providing an independently generated musical tone in response to an audible signal, the combination of an electrical oscillator having a tuning circuit including a plurality of reactance elements, relays operable to couple the reactance elements effectively into the tuning circuit, and tuned circuits respectively connected to the relays and controlled by the pitch of a sound for determining which of said reactances shall be effective in determining the frequency of oscillation of said oscillator.

6. In an electrical musical instrument for providing independently generated musical tones in response to an audible signal, the combination of an electrical oscillator having a tuning circuit including a plurality of reactance elements, voice controlled means for determining which of the reactance elements are to be rendered effective to determine the frequency of oscillation of the oscillator, and means for translating the output of the oscillator into sound.

7. In an electrical musical instrument having

10 an output system including an electroacoustic translating means and amplification means provided with a gain control, the combination of an electrical generator tunable to generate electrical signals corresponding to the semitones of the musical scale, means responsive to the pitch of a controlling sound to tune said generator to the semitone frequency most closely approaching that of the sound, and means to prevent the transmission of a signal to the amplification means whenever the intensity of the controlling sound decreases below a predetermined value.

15 8. In an electrical musical instrument having amplification and electroacoustic translating means, the combination of a microphone, an amplifier coupled to said microphone, a plurality of meshes resonant respectively at the frequencies of the tones of the musical scale, a plurality of relays each including a switch and each associated with one of said resonant meshes and adapted to be operated only when the audible input to said microphone is of a fundamental frequency near that of the resonant frequency of its associated mesh, an oscillator for generating audio frequencies and having a plurality of reactances in its tuning circuit, means operated by said relay switches to determine which of said reactances shall be effective in determining the frequency of oscillation of said oscillator, and selectively operable means for coupling the output of said oscillator to the amplification means.

30 9. The combination set forth in claim 8 in which means are provided to prevent transmission through said amplification means of a signal from said oscillator whenever the output of said amplifier is of such low amplitude as to indicate that no significant audio signal is being supplied said microphone.

40 10. The combination set forth in claim 8 in which there is provided means responsive to the amplitude of the output signal of said amplifier for controlling the gain of said amplification means.

45 11. The combination set forth in claim 8 in which a portion of the signal output of said amplifier is amplified and rectified to produce a voltage varying with the amplitude of the signal output, and in which means are provided to utilize such voltage to control the gain of the amplification means.

50 12. In an electrical musical instrument controlled by an audio-frequency input signal, and having an output amplifier and electroacoustic translating means; the combination of a microphone, and an input amplifier coupled to said microphone to amplify electrical signals generated thereby, said input amplifier having a frequency response characteristic providing progressively decreased gain for signals of increasing frequency, a plurality of frequency responsive meshes coupled to said input amplifier to receive the signal therefrom, said meshes being resonant respectively at the frequencies of the notes of a musical scale, control devices respectively coupled to said frequency responsive meshes, each of said control devices being operated when the audio-frequency input signal has a frequency nearer to that of the resonant frequency of the mesh coupled to such control devices than to the resonant frequencies of the other meshes, electrical means providing electrical tone signals at the various frequencies of the musical scale, and means operated by the control devices for rendering said electrical means effective to transmit to the output am-

plifier electrical musical tone signals having predetermined pitch relationships with respect to the frequencies at which said frequency responsive meshes are resonant.

13. In an electrical musical instrument controlled by an audio-frequency input signal and having an output amplifier and electroacoustic translating means; the combination of an acoustoelectric transducer, an input amplifier coupled to said transducer to amplify the signals generated thereby, a plurality of frequency responsive elements coupled to the input amplifier to receive the signal therefrom, said elements being responsive respectively to the semitone frequencies of the musical scale, control devices respectively coupled to said elements to cause operation of that one of the control devices which is coupled to the one of said elements whose natural response frequency most closely approaches that of the fundamental frequency of the audio-frequency input signal, electrical means for generating any one of a plurality of electrical tone signals of the musical scale, means operated by said control devices for rendering the electrical means effective to transmit to the output amplifier electrical musical tone signals having pitches the same as or octavely related to the frequencies at which said elements are respectively frequency responsive, and means responsive to the amplitude of the input signal for determining the amplitude of the tone signal produced by said electrical means.

14. In an electrical musical instrument controlled by an audio-frequency input signal and having the output amplifier and electroacoustic translating means, the combination of an input amplifier coupled to said transducer to amplify signals generated thereby, said input amplifier having a frequency response characteristic providing progressively decreased gain for signals of increasing frequency, a plurality of frequency responsive devices coupled to the input amplifier to receive the signal therefrom, said devices being responsive respectively at the various notes of a musical scale, electrical means for generating any one of a plurality of electrical tone signals of the musical scale, and means operated by said control devices for rendering said electrical generating means effective to transmit to the output amplifier electrical musical tone signals having octave relationship to the frequencies at which said frequency responsive meshes are resonant.

15. In an electrical musical instrument controlled by an audible input signal and having an output amplifier and electroacoustic translating means, the combination of a microphone, an input amplifier for the signals produced in said microphone, electrical apparatus for generating the tone frequencies of the tempered musical scale, devices for controlling frequencies of the output of said apparatus, means coupled to the input amplifier to receive signals therefrom and operative upon said devices to determine the output frequencies generated by said apparatus, and means coupled to said input amplifier and controlled by the intensity of the audible signal for determining the effective amplitude of the signal output of said apparatus.

16. In an electrical musical instrument, having a variable frequency oscillator provided with tuning means determining its frequency of oscillation, the combination of a plurality of cascaded stages of frequency dividers respectively and successively halving the frequency generated by

said oscillator, a signal transmission system including multi-electrode electron discharge devices coupled to the oscillator and divider stages, an amplifier and electroacoustic translating means, means controlled by an audible signal for operating the tuning means to determine the frequency of oscillation of said oscillator and thereby also the frequency of operation of said divider stages, and means controlled by the amplitude of the audio-input signal to determine the gain of said electron discharge devices, whereby the signal transmitted to the amplifier and electroacoustic translating means will vary in amplitude in accordance with the variations in intensity of the input signal.

17. In an electrical musical instrument having a variable frequency generator capable of generating any one of a plurality of frequencies of the tempered musical scale, means for controlling the output frequency of said generator, a plurality of cascaded frequency divider stages, each of said stages being capable of producing a generally symmetrical wave representative of musical tone qualities having a relatively long series of odd harmonics of substantial amplitude, and means for changing the character of the output wave, said means comprising a rectifier optionally rendered effective to destroy the symmetry of the wave by greatly reducing the amplitude of the peaks on one side of the zero axis without affecting the amplitude on the other side of the axis, whereby the resultant wave will represent a musical tone of the string type in which all audible harmonics are present.

18. In an electrical musical instrument having an apparatus for generating any one of a plurality of the frequencies of the tempered musical scale, an audible signal controlled means for conditioning said apparatus to generate a musical tone signal of pitch nearest that of the audible signal, an output system for said apparatus including an electronic control means, an amplifier, and an electroacoustic translating means, said electronic control means being normally biased to prevent transmission of a signal from said apparatus to said amplifier; and means controlled by the start of the audible signal to change the bias on said electronic control means in a direction to cause the latter to conduct the output signal of said generating apparatus to the amplifier at a predetermined controlled amplitude.

19. The combination set forth in claim 18, in which there is provided manually adjustable means for determining the intensity envelope of the transmitted tones irrespective of the intensity envelope of the controlling initial audible signal.

20. In an electrical musical instrument having an output system including an amplifier and electroacoustic translating means, a plurality of generators producing signals having a fundamental frequency and predominantly the odd harmonics thereof, a rectifier for each of said generators to alter the wave form of the signals generated thereby, and means common to a plurality of said rectifiers for selectively rendering them effective or ineffective.

21. The combination set forth in claim 20 in which said means includes a switch and an impedance operative to adjust the output system of the instrument to reduce the gain thereof whenever the means renders the rectifiers ineffective.

22. In an electrical musical instrument having an output system including an amplifier and electroacoustic translating means, a plurality of generators each producing a signal having a fundamental frequency and predominantly the odd harmonics thereof, a rectifier for each of said generators to alter the wave form of the signals generated thereby, and means common to all of said rectifiers for selectively rendering them effective or ineffective.

23. In an electrical musical instrument, means for electrically converting a uniform pitch glissando input signal into a chromatic scale output signal comprising, a plurality of resonant elements chromatically tuned in the pitch range of the input signal, a local oscillator having a plurality of accurate tuning means for selectively tuning the oscillator to the frequencies of the chromatic scale, said tuning means being coupled to said resonant elements and respectively rendered effective by the excitation thereof, whereby the frequency of said oscillator is changed in finite interval steps of the chromatic scale when a smooth non-chromatic pitch glissando input signal is supplied.

24. In an electrical musical instrument controlled by an audio-frequency input signal, and having an output amplifier and electroacoustic translating means; the combination of a microphone, and an audio frequency input amplifier coupled to said microphone to amplify electrical signals generated thereby, said input amplifier having decreasing gain for input signals of increasing frequency, a plurality of frequency responsive meshes coupled to said input amplifier to receive the signal therefrom, said meshes being resonant respectively at the frequencies of the notes of a musical scale, control devices respectively coupled to said frequency responsive meshes, each of said control devices being operated only when the audio-frequency input signal has a fundamental frequency of substantial amplitude nearer to that of the resonant frequency of the mesh coupled to such control devices than to the resonant frequencies of the other meshes, electrical means providing electrical tone signals at the various frequencies of the musical scale, and means operated

by the control devices for rendering said electrical means effective to transmit to the output amplifier electrical musical tone signals having predetermined pitch relationships with respect to the frequencies at which said frequency responsive meshes are resonant.

25. In an electrical musical instrument, means for electrically converting a uniform glissando input signal into an output signal of discrete tones of the tempered musical scale which comprises, a microphone for the reception of a glissando tone, an audio-frequency amplifier having its input connected to the microphone and having substantially decreased response as the frequency of the input signal increases, a plurality of resonant elements tuned to the pitches of the even tempered scale and extending throughout the pitch range of the input signal, means coupling said resonant elements to the output of said amplifier, electrical generating means for producing tone signals of frequencies of the tempered musical scale, an output system, and means operated by said resonant elements to control transmission of a tone signal from said generating means to said output system, the tone signal transmitted being of pitch the same as or octavely related to that of the resonant element by which it is controlled.
